New Haven, Conn., a corporation of Connecti-
cut

Application April 23, 1930, Serial No. 446,462

27 Claims. (Cl. 177—339)

This invention relates to a functionally and structurally improved traffic control system.

My copending application 227,490, filed October 20, 1927, also relates to a traffic control system and claims to any common subject matter appear in such copending application; the claims in the present application are directed to subject matter not claimed in the copending application.

It is an object of the invention to provide a layout of apparatus by means of which traffic will be expeditiously and automatically handled so that a maximum traffic flow throughout various intersecting lanes may occur and without danger of conflict on the part of traffic moving in different directions.

While the present invention is capable of use in numerous different associations and is accordingly not to be regarded as limited to the following, it is in many respects of primary utility where three or more vehicle lanes merge and regardless of whether traffic after negotiating the intersection wishes to merge into another lane or continue along the same vehicle lane.

A further object of the invention is that of providing an apparatus of extremely rugged and unitary construction which will function over long periods of time with freedom from electrical and mechanical difficulties.

With these and further objects in mind, reference is had to the attached sheets of drawings illustrating one practical embodiment of the invention, and in which:

Fig. 1 is a plan view of a timer by means of which the system may be operated;

Fig. 2 shows a diagrammatic layout of the circuit involved in the present system;

Fig. 3 is a perspective view of the timer as shown in Fig. 1; and

Fig. 4 is a perspective view showing a number of intersecting vehicle lanes, the traffic flow over which will be controlled by the present system.

As afore brought out, the present system is of particular utility when employed in connection with three or more intersecting vehicle lanes. To this end, in Fig. 4, three lanes have been shown. Moreover, with a view to providing a signalling means, a light signal has been illustrated which is in most respects preferable and includes the usual colored bulbs, reflectors and/or lenses, by means of which, for example, red, amber and green may be shown. Obviously, the signalling means might be of any desired character best suited to the needs of the installation, and if—as is in most instances preferable—lights are employed, it will be obvious that in lieu of the cau-

tion period furnished by the yellow or amber provision, any desired arrangement might be resorted to. For example, all lights might be extinguished for a suitable interval; only the red light or lights might be shown for this interval; the red together with the green might be displayed; one or more of the signal indications provided by the lights might be intermittently energized to furnish a flash during this interval, etc.

With regard to the vehicle actuated controls, there has been shown a series of pavement units over which the vehicle passes in order automatically to potentialize the apparatus for a transfer of right of way. To this end, the units preferably each include a circuit breaker which is closed incident to the pressure of the vehicle traversing the unit. Obviously, the reverse might be true or a vehicle actuated control either deliberately manipulated from within the car as for example by the beam from a headlight or spotlight or the sounding of a horn might be employed, or a circuit sympathetic to the passage of a vehicle along the lane might be furnished. Any number of other controls will likewise be apparent as for example that of employing a photoelectric cell against which a beam of light is directed and which beam is necessarily interrupted by the traversal of a vehicle over the lane.

With respect to the timer, it is to be understood that preferably the layout of apparatus provided by the present invention is to be adhered to. Obviously, however, any other desired arrangement might be adopted. Moreover, the relays of the timer might be of any desired character and provision might be made for adjusting their functioning to accord exactly to the conditions peculiar to the particular installation under consideration.

Having the foregoing in mind and referring to the drawings:

Let A, B and C represent three streets or approaches to an intersection. Assume that a preponderance of left turns out of C make it inadvisable to permit traffic to flow from both A and C at the same time. The three phase multi-flow system operates so as to allow traffic to flow from only one of these approaches at a time.

To state the case more specifically: With cars moving through the intersection from A street, no cars are permitted to come out of B or C. If a car is waiting to move from C it will be given the green light when A yields the green light either thru the cessation of traffic on A street, or due to the expiration of the A street over-all

- limiting period. If, on the other hand, no car is waiting on C street but one is waiting on B street, the car on B street will be given the green light as soon as A street has yielded its green light.
- 5 The streets will, in a predetermined order, be given the opportunity to take the green light, but no street will take the light when the opportunity is offered unless cars are actually waiting on that street or no cars are waiting on any other street.
- 10 The system also "remembers" when it breaks a stream of traffic due to the expiration of the overall period and leaves a "call" for the green light on that street which insures that the right of way will return to that street after the other streets have been given their turn to take the green light.
- 15 Figures 1 and 2 show the details of the mechanism and the electrical circuit comprising one embodiment of this system. The specific condition of the mechanism shown is that which prevails when the green light is showing on B street and no cars are waiting on either A street or C street.
- 20 Referring to Figure 1.—F, M, and P are insulated levers pinioned respectively at f, m, and p. When lever F is moved to the left so that the contacts to its left are made and those to its right are broken, A street is given the opportunity to take the right of way. Similarly when lever M is moved in a like manner, B street is given the opportunity to take the green light. And when lever P is moved in a like manner, C street has its opportunity to take the green light.
- 25 30 The levers F, M, and P are operated by the cams shown on the shaft 9' to the rear of the levers. These cams are fixed to the shaft and revolve with it. But they are angularly displaced so that as the shaft revolves at uniform speed the levers are moved in the order F, M, P. Each lever completes its cycle of motion (from the position of rest as shown by lever F to the left until it reaches the position shown by lever M, thence back to its initial position of rest) before the next one begins its cycle. This prevents more than one flow of traffic at a time.
- 35 The cam shaft is driven by the motor 10', worm shaft 11', worm wheel 12', clutch 13' and 16', and bevel gears 14' and 15'. The motor, the worm wheel and one face 13' of the clutch run all the time. To the other face 16' of the clutch is attached the bevel gear 14' which engages bevel gear 15' on the cam shaft 9' and a disk having three projections 17', each in turn engaging a pawl 18', operated by a magnet 19'. The clutch pressure is so adjusted that if the pawl on the magnet armature were pulled away from the projection with which it engages motion would be transmitted from the motor thru the clutch to the cam shaft thus causing the levers F, M, and P to move sequentially. However, when the armature is attracted to the magnet, thus engaging the pawl with one of the projections on the disk, the cam shaft will be stopped and the clutch will slip. The projections are so located that the cam shaft will be held in such a position that one of the levers F, M, or P will be at its extreme position of travel as these projections, in cooperation with the pawl.

it is given the green light. Their functions are as follows:

Time delayed relay W, when operated, fixes the period during which a continuous stream of vehicles can hold the green light.

Time delayed relay X insures each vehicle a predetermined period during which to cross the intersection.

Time delayed relay Z governs the period during which the yellow light is displayed.

The operation of transferring the green light from one street to another is accomplished in the following manner. Suppose that B street has the green light and a car operated the pavement contact system on C street. Relays N, O and T will be operated. The operation of these relays so connects time delayed relays that the operation of relay X or relay W will act to yield the green light on B street by causing relay S to be de-energized. The opening of relay S turns out the green light on B street and turns on the B street yellow light at the same time energizing the time delayed relay Z. At the end of the time for which time delayed relay Z is set it will operate thereby opening the circuit to the B street yellow light and the circuit 113 to the clutch magnet 19'. This causes clutch magnet armature to fall back thereby disengaging the pawl from the projection on the wheel attached to the shaft which, thru the bevel gear, moves the cam shaft. The clutch now stops slipping and the cam shaft revolves thus allowing lever M to return to its position of rest (with right contacts made and the left contacts broken).

This turns on the B street red light. The cam shaft continues to revolve until the next cam moves the lever P to its left position. During the period between the breaking of the left contact system of lever M and the making of the left contact system of the lever P, the time delayed relays W and X have been de-energized and are in their unoperated position. When the contacts to the left of lever P are closed, current passes thru the contact system of relays O, X, and W to energize relay S which operates immediately. The operation of relay S energizes the clutch magnet which operates its armature causing the pawl to engage the next projection on the wheel, which projection is located in such a position that the cam shaft is stopped when lever P is at its extreme left position. This closes the left contact system of lever P, opens the right contact system of lever P, thus extinguishing the C street red light, lighting the C street green light and connecting the time delayed relays W, X and Z into the C street circuits where they will now function just as they did when connected to the B street circuit.

To trace a transition in detail, let us start with the circuit in the condition shown in Figure 2. Assume that no cars operate the B street pavement contacts K1 and K2 and that none are waiting on A or C streets. Relay K will remain de-energized thus keeping time delayed relay X energized by current flowing thru contacts K6 and K1, wire 29, contacts M15 and M16, wires 76 and 105, relay X, wire 102, contacts S3 and S4 and wires 107 and 110. At the end of the time for which it is set relay X will operate causing armature X8 to make contact with X9 and armature X7 to break from contacts X5 and X6.

The separation of armature X7 from contact X6 opens one circuit feeding current to relay S as follows: wire 32, armature L4, contact L3,

wires 51 and 86, contacts M7, M8, wires 73, 89, 99, contact X6, armature X7, armature W2, contact W1, wire 97, relay S and wire 110. But there is a circuit parallel to the one just described which still keeps relay S energized. This second circuit passes thru the back contact of the T relay and may be traced as follows: wire 15, contacts M13 and M14, wire 74, armature T2, contact T1, wire 98, armature W2, contact W1, wire 97, relay S and wire 110. The relay S will remain energized until its current is stopped thru either the separation of armature W2 from contact W1 or armature T2 from contact T1. It is evident from an inspection of Figure 2 that relay T will be operated whenever a car has crossed a pavement unit 15 on any street against a red light. For instance, assume that a car operates the pavement unit on C street; relay T will be energized and armature T2 will break from contact T1. This is accomplished as follows: a car operates the C street 20 pavement contact unit, causing current to flow so as to energize relay N thru the following path: wire 38, contacts N1 and N2, wire 39, relay N and wires 40 and 41. Armature N3 now makes with contact N4 and armature N6 breaks from 25 contact N7 and makes with contact N5. Relay N will receive current to remain energized (after contacts N1 and N2 have separated due to the passage of the vehicle) thru wires 41, 40, 39, 42, armature N3, contact N4, wire 43, contacts P20 30 and P19, wires 60 and 20. Relay O is now supplied with current thru wires 41, armature N6, contact N5, wires 44, 47, relay O and wire 46. Armature O1 now makes with contact O2 and armature O4 breaks from contact O5 and makes 35 with contact O3. The operation of relay O energizes relay T thru the following circuit: wire 48, armature O1, contact O2, wire 49, contacts P22, P21, wire 63, relay T and wire 109. The operation of relay T causes armature T2 to break from T1 40 and make with contact T3. However, the fact that relay L is operated in Figure 2 does not provide a path for current to relay T because of the separation of contacts M21 and M22. It follows from these conditions that relay T will 45 be operated whenever a car is waiting against a red light. The operation of any one of relays E, L, or O when a green or yellow light is showing on its corresponding street, will not energize relay T because current in each of these circuits 50 passes thru a set of contacts on the right side of the lever, which contacts will always be separated when said lever is at the left as it must be when the yellow or green light is displayed on the street to which its contact system is connected. 55

Now both of the current paths feeding relay S are broken. One between contact T1 and armature T2 because a car is waiting on C street and the other between contact X6 and armature X7, because no car has crossed the pavement unit on 60 B street (which has the green light) during the period in which time delayed relay X is set to operate. Hence relay S is de-energized.

Armature S6 now breaks contact with S5 and makes with contact S7 and S8, armature S3 65 breaks from contact S4 and armature S2 makes contact with S1. The separation of S6 from S5 extinguishes the green light on B street which has been receiving current thru armature S6, contact S5, wire 62, contacts M4, M3, wires 36 70 and 37. The yellow light on B street is now supplied with current thru wires 37, 35 contacts M5, M6, wires 64, 88, contact Z3, armature Z4, wire 100 contact S1, armature S2, wires 89, 73, contacts M8, M7, wires 86, 51, contact L3, armature 75

L4, and wire 32. Time delayed relay Z is now energized thru wires 106, 108, contact S7 and armature S6. The separation of armature S3 from contact S4 did not cause time delayed relay X to be de-energized because armature X8 made contact with X9 when relay X operated. Thus before the path thru wires 110, 107, armature S3, contact S4 and wire 102 to relay X was broken, it was paralleled by the path thru wire 103, armature X8 and contact X9.

At the end of the period for which it is set, time delayed relay Z operates causing armature Z4 to break from contact Z3, thus extinguishing the B street yellow light for which the current path has been traced thru armature Z4 and contact Z3. Armature Z2 also breaks from contact Z1 thus releasing the clutch magnet which has been energized thru wire 32, armature L4, contact L3, wires 51 and 86, contacts M17, M8, wires 73, 89, 99, armature Z2, contact Z1, wire 113 to clutch magnet, thence to positive power.

The clutch magnet armature now drops back, the pawl disengages from the wheel projection and permits the cam shaft to revolve. The cam holding lever M in its left hand position revolves permitting lever M to be pulled into its right hand position. This permits the following contacts to separate; M1 from M2, M3 from M4, M5 from M6, M7 from M8, M9 from M10, M11 from M12, M13 from M14, M15 from M16, and M17 from M18. The contacts which now make connection are: M19 with M20, M21 with M22, M23 with M24, and M25 with M26.

In Figure 2, it is noticeable that the contacts associated with the levers F, M and P are so located that all contacts associated with a given lever are not operated at the same time. The contact system of lever F is in the position of its contacts relative to each other and relative to the lever F itself, at any given position in its cycle of operation exactly the same as the contact systems associated with levers M, and P when either of these levers is at the same position in its cycle of operations.

Hence when lever M has moved to its extreme right position, its contact system will be in the same condition as that of the contact system associated with levers F and P as shown in Figure 2. From the positions of the corresponding contacts associated with lever F, it can be seen that as lever M moves to the right, the first change of condition in its contact system will be the separation of contacts M3 from M4, M5 from M6, and M11 from M12. The separation of M3 from M4 disconnects the green light on B street, and the separation of contact M5 from M6 disconnects the B street yellow light so that neither of these lights will be energized during the process of giving the green light to another street. The circuits feeding both of these lights were traced before, hence to avoid needless repetition they will not be traced again.

The separation of contact M11 and M12 opened the circuit which held relay L energized. This circuit has been traced before which makes it unnecessary to trace it again at this point. Armature L1 now breaks from contact L2 and armature L4 breaks from contact L3 and makes contact with L5 thereby lighting the B street red light thru wire 32, armature L4, contact L5, and wires 33 and 37. Next, contact M19 makes contact with M20 and contact M25 makes contact with M26. Under the conditions assumed, i. e., a car waiting on C street and none on B street the closing of these contacts has no immediate

effect on the system. The next occurrence in order of sequence is the separation of contact M7 from M8, M9 from M10, M13 from M14, M15 from M16, M17 from M18 and the making of contacts M21 with M22 and M23 with 24.

The separation of contact M7 from M8 and M9 from M10 have no immediate effect on the system. The separation of M13 from M14 de-energizes time delayed relay W causing it thus to return to its zero position. Due to the fact that under the conditions assumed, this relay had not been energized long enough to operate, its return to the zero position has no immediate effect on the system. The separation of contact M15 from M16 and M17 from M18 de-energized time delayed relay X which was energized thru two parallel circuits with M15 and M16 in one and M17 and M18 in the other. These may be traced as follows: Wires 25, 26, armature K6, contact K1, wire 29, contact M15, M16, wires 76, 105, relay X, contact X9, armature X8 and wire 103. The other parallel circuit being armature S6, contact S8, wires 79, 78, contacts M17, M18, wires 77, 105, relay X, contact X9, armature X8 and wire 103.

The making of contact M21 with M22 has no immediate effect on the system as the circuit in which they are included has already been opened between armature L1 and contact L2. The making of contact M23 with M24 likewise has no immediate effect on the system, nor does the making of armature X7 with contacts X5 and X6 have any immediate effect.

The condition of the system is now as follows: Contact relays D, E, K, L, and S are in their unoperated positions. Contact relays N, O, and T are energized and in their operated positions.

Time delayed relays W and X are in their unoperated positions and time delayed relay Z is in its operated position. Levers F, M and P are in their extreme right hand positions with all right hand contacts made and all left hand contacts open.

The clutch magnet is de-energized, its armature is back, the pawl is disengaged from the clutch wheel projections and the cam shaft is therefore revolving. The cam associated with lever M has just released this lever which is now in its right hand position. The cam associated with lever P is about to move lever P from its right hand position into its left hand position.

Lever P now moves to the left. The first contact change is the separation of P21 from P22 and P23 from P24. The separation of P21 from P22 de-energizes relay T, the current for which has previously been traced thru contacts P21 and P22. Relay T gets no current thru either of the other two parallel paths as armatures E1 and L1 are separated respectively from contacts E2 and L2. Armature T2 now breaks contact with T3 and makes contact with T1. This has no immediate effect on the system. The separation of contacts P23 from contact P 24 extinguished the C street red light (Rc) which has been supplied with current thru wires 55, 52, 96, contacts P23, P24 and wire 56.

Next the following contacts make: P1 with P2, P7 with P8, P9 with P10, P13 with P14, P15 with P16, P17 with P18. The contact between P1 and P2 has no immediate effect on the system inasmuch as at present, armature X11 is separated from contact X10 due to the fact that time delayed relay X is de-energized and reset to its zero position.

The making of contact P7 with P8, energized

relay S thru the following path: wire 48, armature O4, contact O3, wires 50 and 85, contacts P7, P8, wires 73, 89, 99, contact X8, armature X1, armature W2, contact W1, wire 97, relay S and wire 110.

Armature S2 now breaks contact with S1, armature S3 makes contact with S4. Armature S6 breaks contact with S7 and S8 and makes contact with S5.

10 Time delayed relay Z is de-energized thru the separation of armature S6 from contact S7. The circuit energizing relay Z consisting of armature S6, contact S7, wire 108, relay Z and wire 106.

Armature Z4 now makes contact with Z3 and armature Z2 makes contact with Z1. The contact between armature Z4 and contact Z3 has no immediate effect on the system as this circuit has been broken by the separation of armature S2 from contact S1.

20 The clutch magnet is now energized thru wire 48, armature O4, contact O3, wires 50 and 95, contacts P7 and P8, wires 73, 89, 99, armature Z2, contact Z1 and wire 113. The clutch magnet armature now pulls up and its pawl is brought into position to catch the next passing projection on the clutch wheel. This projection is so located that it will stop the cam shaft (and hence the lever P) when lever P reaches its extreme left hand position.

30 Time delayed relay W is now energized thru wires 110, 107, armature S3, contact S4, wires 102, 101, relay W, wire 104, switch W5, wire 74, contacts P14, P13 and wire 75.

As lever P continues toward the left contact 35 P19 separates from P20 and contact P25 separates from P26. The separation of P25 from P26 has no immediate effect on the system. The separation of P19 from P20 de-energizes relay N, the holding current for which has previously 40 traced thru this pair of contacts. Armature N3 now separates from contact N4 and armature N6 separates from contact N5 and makes contact with N7. The separation of armature N3 from contact N4 has no immediate effect on the system.

45 The holding current for relay O was traced thru a circuit including armature N6 and contact N5. The separation of these does not however de-energize relay O as this relay is now fed current thru another path including contacts P7, P8, P9 and P10 which closed before relay N was de-energized. This new path feeding relay O is as follows: wire 48, armature O4, contact O3, wires 50, 95, contacts P7, P8, wires 73, 89, 99, contact 50 X8, armature X1, contact X5, wires 81, 71, contacts P10, P9, wires 91, 92, 47, relay O and wire 46.

The contact of armature N6 with N7 energizes time delayed relay X thru wire 41, armature N6, contact N7, wire 45, contacts P15, P16, wires 76, 105, relay X, wire 102, contact S4, armature S3, and wires 107 and 110.

55 The further movement of lever P causes contacts P3, P5 and P11 to make respectively with contacts P4, P6, and P12. The contact of P3 with P4 lights the C street green light (Gc) thru wire 55, Gc, wire 54, contacts P3, P4, wires 62, 114, contact S5, and armature S6. The making of contact P5 with P6 has no immediate effect 60 on the system. C street now has the right of way and a red signal light is exposed on all other streets.

70 This covers the operation of the system to transfer the right of way from B street to C street.

If instead of a car calling for right of way by operating the pavement unit on C street, one had done so on A street, the transition of right of way from B street to A street would have been the same with relays D and E with associated contacts substituted for relays N and O and lever F with associated contacts substituted for lever P.

75 However, the location of the cams operating levers F, M and P is such that after the return of lever M and before the operation of lever F, lever P would have to be moved into its left hand position and returned to its right hand position of rest.

Bearing in mind that as we are now assuming that no car operated the C street pavement units, relays N and O would be in their unoperated positions as shown in Figure 2, we will trace the action of the system enough to show that the lever P would not, under the assumed conditions, stop in its left hand position and that the green light and the yellow light on C street would not be lighted nor would the C street red light be extinguished during this transition.

80 First to show that lever P would not stop in its left position: Referring to the action of the system previously outlined in transferring the right of way from B street to C street, it was shown that the clutch magnet was operated to stop the cam shaft thru the releasing of time delayed relay Z due to the operation of relay S which received its energy thru a circuit including armature O4 and contact O3. Since relay O is now de-energized, armature O4 is not in 85 contact with O3 and relay S is therefore not energized when lever P moves into its left hand position. The fact that relay S remains de-energized leaves relay Z energized and hence, the circuit feeding the clutch magnet remains 90 open between armature Z2 and contact Z1.

Hence, the clutch magnet remains de-energized, the pawl does not engage the projection on the cam shaft wheel and the cam shaft continues to revolve thereby allowing lever P to return to its 95 position of rest at the right hand as it is shown in Figure 2. The cam shaft now continues to revolve until lever F is moved to its left hand position when it will be stopped. The action which stops the cam shaft and that which extinguished the A street red light and turns on the A street green is similar to that outlined in 100 explaining the transition from B street to C street, and may be followed by substituting in that account each part associated with A street for the corresponding part associated with C street.

105 The C street red light, the circuit for which was before traced thru contacts P23 and P24 is not extinguished this time when these contacts 110 temporarily separate because it is fed thru the parallel circuit including wire 48, armature O4, contact O5, wire 52, R_c and wire 55.

The circuit for the yellow light on C street was previously traced thru armature Z4 and contact 115 Z3. Since relay Z remains energized while lever P is in its left position as we have just shown, the circuit to the C street yellow light remains open and Yc is not lighted.

The C street green light circuit was previously 120 traced thru contact S5 and armature S6. The fact that these remain separated while lever P is in its left hand position causes the C street green light to remain unlighted.

125 The cam shaft now continues to revolve until 75

lever F has been operated to give A street the green light.

Earlier in this description, it was stated that time delayed relays W and X were connected into the circuit in such a way that they would always act to limit the time during which a given street could hold right of way. The transfer of the connections of these relays from one street to another has been traced in detail. We shall now 10 consider the way in which they act to limit the time during which a street can have the green light. Referring to Figure 2, which shows the system as it would be if B street had the right of way and no cars were waiting on either A or C 15 streets, the relays W and X are as shown in this diagram connected through the contacts associated with lever M to the relays K and L which are controlled in part by vehicles operating the B street pavement unit K1. First, to explain the 20 action of time delayed relay X. The function of relay X as was mentioned before is to provide that any car which has crossed a pavement unit shall be given a certain pre-determined period during which to cross the intersection. Before 25 discussing in detail how this is accomplished, it would be well to notice a few features of the construction of this relay. Armature X11 separates from contact X10. The mere de-energization of relay X does not cause armature X11 to 30 separate from contact X10, however. To have this separation take place it is necessary for relay X not only to be de-energized, but to have actually re-set itself to its zero position.

One of the functions of armature X11 is to 35 insure that a car which operates a pavement unit when it is approaching a green light shall be given its full protective period. In other words, to insure that time delayed relay X actually re-sets to its zero position rather than to be stopped 40 part way back. To explain how this is accomplished, let us assume that relay X has been energized over half of the period at the end of which it has been set to operate. Under these conditions, armatures and contacts associating with 45 relay X will be in a position shown in Figure 2. This relay is now receiving its current through the following path: wires 25, 26, armature K6, contact K7, wire 29, contacts M15, M16, wires 76, 105, relay X, wire 102, contact S4, armature S3, and wires 107 and 110.

A vehicle operating the B street pavement unit 50 would cause K1 to make with contact K2 thereby energizing relay K thru wire 21, pavement unit K1, K2, wire 22, relay K, wires 24 and 25. Armature K3 now makes contact with K4 and armature K6 breaks contact from K7 and makes contact with K5. The separation of armature K6 from contact K7 de-energizes time delayed relay X, the circuit for which has just been traced 55 thru this armature and contact. The completion of the circuit between armature K3 and contact K4 provides a path for current to keep relay K energized, even though the vehicle has passed allowing K1 to separate from K2, until time delayed relay X shall have actually set back to its zero position. The path for this holding current is as follows: wires 25, 24 relay K, wire 23, armature K3, contact K4, wire 27, contacts M1 and M2, wires 61, 80, armature X11, and contact X10. 60 When relay X has actually set back to its zero position, armature X11 separates as was explained previously from contact X10 thereby opening the circuit thru which relay K is kept energized; thus permitting armature K3 to separate from contact K4 and armature K6 to separate from con-

tact K5 and make with contact K7. The making of armature K6 with contact K7 again energizes time delayed relay X.

Another function of armature X11 and contact X10 is to provide that relay K shall remain energized if a car crosses the B street pavement unit during the period when the right of way is leaving B street, namely, when the green light on B street has been extinguished and the yellow light, on B street is burning, warning traffic that the red light is about to be shown. In order to accomplish this, contacts M19 and M20 are so adjusted that as lever M moves to the right, M19 will make with contact M20 before contact M1 breaks from contact M2. It has been previously explained that relay X once it has operated to yield the right of way, locks itself in the operated position thru armature X8 and contact X9 until the lever (M, in this case) thru which this relay is energized has returned to its normal position after having yielded the right of way. Due to this fact, armature X11 remains in contact with X10 until contact M19 has made with contact M20. This insures current to keep relay K energized until the right of way shall have again returned to B street.

Time delayed relay W will also yield the right of way when it operates thru the separation of armature W2 from contact W1 (armature W2 and contact W1 are part of the circuit which has been previously traced for the energization of relay S, the release of which acts to yield the right of way). The circuit as shown in Figure 2 provides that relay W shall be energized as soon as right of way is given to any street and shall remain energized until such right of way is transferred to another street. The current for relay W can be traced in Figure 2 as follows: wire 75, contacts M13, M14, wire 74, switch W5, wire 104, relay W, wire 102, contact S4, armature S3, and wire 101. When time delayed relay W operates, armature W3 makes contact with W4 before armature W2 breaks from contact W1. The connection between armature W3 and contact W4 provides an auxiliary circuit to keep relay W energized after a main circuit has been broken by the separation of armature S3 from contact S4. This circuit may be traced thru wires 103, 101, armature W3 and contact W4 which circuit is in parallel with that feeding the relay thru armature S3 and contact S4. Due to the fact that time delayed relay W remains energized shown in Fig. 2, as long as right of way is given to any street, it is evident that it provides a limitation on a period during which a steady stream of cars can hold the right of way on any street. If switch W5 were thrown in the position indicated by the dotted lines, relay W would not be energized as soon as right of way was given to any street, but would be energized only after a car had approached the intersection operating the vehicle actuated control provided by the pavement units on one of the streets showing a red light. An inspection of Figure 2 will show why this is so. The current to energize relay W was traced thru wire 74, switch W5 and wire 104. If switch W5 is thrown in the position indicated by the dotted lines, it is obvious that the current, in order to get from wire 74 into wire 104 must pass thru armature T2 and contact T3. Armature T2 will be in contact with T3 only as has been previously explained when a car is waiting for right of way after having crossed a pavement unit, subsequent to which crossing, it was not given a full protective period of green light. A 75

car might cross the pavement unit on a given street against the green light toward the end of the period of operation of time delayed relay W. If it should happen that relay W should act to 5 yield the right of way before this car had been given the full protective period for crossing the intersection, the system is so arranged that the right of way will return to this street at the earliest possible moment to take this car across. 10 It will be remembered that this protective period is fixed by time delayed relay X. In the case just mentioned, the car thru the operation of the pavement unit would re-set relay X thereby causing X7 to make with contacts X5 and X6. Let 15 use assume that this car has approached the intersection from B street. Before it crosses the intersection, relay W acts to yield the right of way. Under these conditions, the movement of lever M to the right will not unlock relay L. It will 20 be remembered that in the previous instance of the transfer of the right of way from B street to C street, relay L was de-energized when contact M11 separated from contact M12. However, this 25 time the separation of contact M11 from M12 will not open the circuit feeding relay L because of the fact that armature X7 is making with contacts X5 and X6. Relay L will, after contact M11 has broken from contact M12, and before contact M25 has made with contact M26, be fed 30 current thru the following circuit: wire 32, armature L4, contact L3, wires 51, 86, contacts M7, M8, wires 13, 89, 99, contact X6, armature X7, contact X5, wire 81, contacts M10, M9, wires 83, 57, and 31, relay L and wire 30. Before contact 35 M7 separates from contact M8 and contact M9 separates from contact M10, thus interrupting the circuit just outlined, contact M25 will have made contact with M26, thereby providing a new path for current to keep relay L energized before the old one is broken. This new unit may be 40 traced as follows: wire 32, armature L4, contact L3, wires 51, 85, contacts M25, M26, wires 84, 83, 57, 31, relay L and wire 30. Relay L will therefore remain energized and cause the right of way 45 to return to B street at the first available opportunity. The general plan by which provision is made for the yielding of the right of way may be roughly outlined as follows: as has been shown before, the releasing of relay S will act to yield the right of way on a given street, relay S will 50 be released whenever armature W2 separates contact W1 or when armature X7 has separated from contacts X5 and X6 and armature T2 has separated from contact T1. Thus it will be seen that the 55 system as shown in Figure 2, the right of way will leave the given street after it has been held by that street for a predetermined period, thru the separation of armature W2 from contact W1. If at any time within this period, the last car to 60 cross the pavement unit has been given its full protective period and relay X has operated to separate armature X7 from contacts X5 and X6, relay S is still energized by current flowing thru armature T2 and contact T1. This means that 65 when a stream of cars passing thru the intersection on a given street has crossed the intersection, the right of way will be transferred to any other street on which a car may approach without delay because of the fact that the operation 70 of the pavement unit by said car will energize relay T thereby causing armature T2 to separate from contact T1 and break the remaining circuit supplying current to relay S. This will cause the green light to be extinguished on the 75 street which has been holding the right of way

and the yellow light to be shown thereon, after which the red light will show, whereupon the right of way will be transferred to the street on which the car is waiting.

In the absence of traffic on any of the lanes, if it is assumed for instance that traffic was last present and has just cleared on street B and the green signal is showing on street B with red signals on streets A and C as indicated in Figures 1, 2 and 3, there are two modes of operation as follows:

A. *With switch W5 in the up position as indicated in Figure 2*, time delay relay W will be energized and timing its interval before operating its contacts, and with proper time setting 15 time delay relay X will have been energized for its full interval and will operate its contacts, separating X7 from X5 and X6. Since we are assuming no further traffic on B time relay X will remain energized in this operated position. 20 Since we are assuming no traffic on A or C, relay T will remain deenergized with T1 connected to T2. Now when relay W completes its time interval and operates its contacts, separating W2 from W1 and connecting W3 with W4 the holding circuit for relay S is broken as already described, and relay S is deenergized, which in turn energizes relay Z through the closing of contacts S6 and S7. The green signal on B is now extinguished and the yellow signal lighted for the time 30 interval of time delay Z, as already described. At the end of its time interval relay Z operates its contacts, breaking the circuit to the clutch magnet 19' thus allowing the clutch pawl to release and the cam shaft to rotate, and lever M 35 to be restored to rest opening its left contacts and closing its right contacts. The opening of contacts M13—M14 deenergizes time relay W, which in turn closes contacts W2—W1; and the opening of contacts M15—M16 and M17—M18 deenergizes 40 relay X closing contacts X5—X7 and X6—X7. As soon as the next lever P is shifted to the left by the cam shaft, and contacts P13—P14 are closed, the relay S is energized. The resulting opening of contacts S6—S7 deenergizes time relay Z, which 45 in turn energizes the clutch magnet 19' by the closing of contacts Z1 and Z2, causing the cam shaft to stop with the lever P in the left position, and giving the green signal to C street. The circuit energizing the clutch magnet may be traced 50 as follows: wire 116, magnet 19', wires 115, 113, contact Z1, armature Z2, wire 99, contact X6, armature X7, wires 117, 98, contact T1, armature T2, wire 14, contact P14—P13, wire 75. Time relays W and X are now again energized and start 55 timing the C street green interval. If there continues to be no traffic, relay W will again cause shift of the right of way at the end of its time interval, and the cam shaft will next stop with lever F in the left position giving the green signal 60 to A street. Thus with switch W5 in the up position and in the complete absence of traffic, the right of way will be shifted periodically to each street in order for a predetermined time interval governed by time relay W. 65

B. *With switch W5 in the down position as indicated by dotted lines in Figure 2*, time delay relay W will not be energized unless relay T is energized by traffic approaching the red signal on street A or street C, the right of way being now 70 on street B as assumed above. Therefore, with the switch W5 in this down position time relay W will remain deenergized and the right of way will remain indefinitely on street B in the absence of traffic on the other streets. This condi- 75

- tion is independent of the presence or absence of traffic on street B with the green signal. Although in the absence of B street traffic the time relay X continues to be energized and thus opens its contacts X5—X7 and X6—X7 at the end of its interval, the parallel circuit through the contacts T1—T2, maintained as long as no traffic approaches on streets A and C, will hold relay S energized and retain the right of way on street B.
- 10 The same general conditions of operation described for right of way on street B apply when the right of way is on one of the other streets, and if the right of way is shifted from street B to street C by the approach of a vehicle on street C for instance, then the right of way will remain on street C as long as there is no traffic present on streets A and B. Briefly stated, with the switch W5 in the down position the right of way remains on the street where it was last used by traffic until it is required by traffic on another street. In addition the right of way may be held on the former street by successive actuations on that street within the protection interval timed by relay X, for a maximum interval 20 timed by relay W after the first actuation on the latter street.
- 15 It is pointed out that if switches D1—D2 and K1—K2, for instance, under the system of operation described under heading B above, are kept closed continuously, then the right of way will normally shift periodically, and for predetermined intervals governed by the time relay W, between two of the streets A and B, in the absence of actuation on the other street C, but that upon 25 actuation on street C in any one cycle a right of way period will be given to street C in its order within that cycle.
- 20 From the foregoing it will be understood that a system and timer is provided by means of which the objects as specifically aforementioned, are achieved. It is obvious that with the arrangement of parts as described, a minimum of traffic interruption will occur incident to the handling of the traffic flow in a manner such that danger of collision will be reduced to a minimum.
- 25 The right of way is maintained for a period adequate to permit an approaching vehicle to negotiate the intersection and in the event of 30 no traffic awaiting right of way in one lane the apparatus does not unnecessarily accord right of way to that lane, but transfers the right of way to the lane awaiting the same.
- 35 It will be understood that any number of changes and rearrangements of the parts might be resorted to without departing from the spirit of the invention as defined by the claims.
- 40 Having described my invention, what I claim as new and desire to secure by Letters Patent, is:

- 60 1. A traffic control system for more than two interfering traffic lanes including signaling means to accord right-of-way over any one lane while interrupting right of way over the other lanes, vehicle actuated controls associated one with each of said lines, means including timing mechanism connected to said signalling means and vehicle actuated controls and having one operating cycle for said signalling means to sequentially accord and interrupt right of way 65 to the succeeding vehicle lanes when activated, and means cooperating with the second named means for activating the latter responsive to actuation of the respective vehicle actuated controls to cause right of way to be accorded to the next 70 succeeding vehicle lane in which a vehicle actu-

ated control has been actuated, and means to maintain interruption of right of way through said signalling means in any intervening lane in which the vehicle actuated control has not been actuated.

6. A traffic control system for more than two interfering traffic lanes including signaling means to accord right of way over any one lane while interrupting right of way over the other lanes, vehicle actuated controls associated one with each of said lanes, means including timing mechanism connected to said signalling means and vehicle actuated controls and having an operating cycle for said signalling means to sequentially accord and interrupt right of way 10 to the succeeding vehicle lanes responsive to actuation of the several vehicle actuated controls, and means forming a part of said timing mechanism to cause said accord of right of way 15 to any one lane and interruption of right of way 20 to the other lanes to continue for minimum periods of time and in response to actuations of the control associated with the lane currently having right of way.

3. A traffic control system for more than two interfering traffic lanes including signaling means to accord right of way over any one of said lanes while interrupting right of way over the other lanes, traffic actuated means in the lanes and operating means connected to both the signalling means and traffic actuated means and operating in response to functioning of the latter for causing the signalling means to shift right of way to that lane in which such traffic actuated means has operated.

4. A traffic control system for more than two interfering traffic lanes including signaling means to accord right of way over any one of said lanes while interrupting right of way over the other lanes, traffic actuated means in the lanes, operating means connected to both the signalling means and traffic actuated means and operating in response to functioning of the latter for causing the signalling means to shift right of way to that lane in which such traffic actuated means has operated and timing means forming a part of said operating means for preventing any further transfer of right of way indication for minimum periods of time.

5. A traffic control system for more than two interfering traffic lanes including signaling means to accord right of way over any one of said lanes while interrupting right of way over the other lanes, traffic actuated means in the lanes, operating means connected to both the signalling means and the traffic actuated means and operating in response to functioning of the latter for causing the signalling means to shift right of way to that lane in which such traffic actuated means has operated, timing means for maintaining each right of way indication for at least a minimum period of time and means whereby said period may be extended by actuations of the traffic actuated means located in the lane which is being accorded right of way.

6. A traffic control system for more than two interfering traffic lanes including signaling means to accord right of way over any one of said lanes while interrupting right of way over the other lanes, traffic actuated means in the lanes, timing means connected to both the signalling means and the traffic actuated means for maintaining the displayed right of way indication for at least a minimum period of time, means forming a part of said timing means whereby said pe-

5 riod may be extended by further actuations of the traffic actuated means of the lane which is being accorded right of way, further means also forming a part of said timing means and operating in response to actuations of a traffic actuated means in another lane for limiting such period of right of way indication and means connected to said timing means for causing shifting of right of way indication to such other lane upon 10 the expiration of such period of right of way indication.

7. A traffic control system including, in combination, a signalling means to be disposed adjacent the intersection of more than two mutually interfering traffic lanes and to accord right of way to traffic moving over one of said lanes while interrupting right of way to traffic moving over the other lanes, a timer connected to said signalling means to operate the same, a traffic 15 actuated control for each of at least two of said lanes and connected to said timer, and means forming a part of said timer and acting in response to actuation of any one of said controls to cause said signalling means to transfer right 20 of way in favor of the lane whose control has been actuated.

8. A traffic control system including, in combination, a signalling means to be disposed at the point of intersection of more than two traffic 30 lanes and to accord right of way to traffic moving over one of said lanes, while interrupting right of way to the other lanes, traffic actuated controls disposed in the lanes and in advance of such intersection, a cyclic timer connected to said signalling means and having more than two operating positions in its cycle corresponding to said more than two traffic lanes and adapted when activated to operate through such cycle to operate the signalling means to accord right 35 of way to the several lanes sequentially and adapted when not activated to remain in the operating position to which it was last activated, and means connecting said controls to said timer to activate the latter from one position to another in response to a vehicle actuating the 40 former.

9. A traffic control system for more than two interfering traffic lanes including signalling means to accord right-of-way to one lane while interrupting right-of-way to the other lanes, switch means for each of said lanes, timer means operating when said switch means are closed for two of said lanes to cause said signalling means to cyclically accord right-of-way alternately for predetermined periods to each of said 45 two lanes, and means cooperating with said timing means when the switch means for a third lane is closed to cause the transfer of right-of-way to said third lane for a predetermined period followed by the resumption of cyclic operation.

10. A traffic control system for more than two interfering traffic lanes including signalling means to accord right-of-way to one lane while interrupting right-of-way to the other lanes, traffic actuated means in one of said lanes, timing means operating to cause said signalling means to cyclically accord right-of-way successively for predetermined periods to each of said lanes, and means to interrupt the cyclic 50 operation to give the right-of-way to said one lane in response to actuation of said traffic actuated means.

11. A traffic control system for more than two interfering traffic lanes including signalling 55 means to accord right-of-way to one lane while

interrupting right-of-way to the other lanes, traffic actuable means in each of said lanes, timing means operating to cause said signalling means to cyclically accord right-of-way successively for predetermined periods to each of said lanes in the absence of actuation, and means to interrupt the cyclic operation to give the right-of-way to one of said lanes substantially forthwith in response to actuation in said one lane.

12. A traffic control system for more than two interfering traffic lanes including signalling means to accord right-of-way to one lane while interrupting right-of-way to the other lanes, traffic actuable means in each lane, means to transfer right-of-way from one lane to another lane in response to actuation of the traffic actuable means in the latter lane, and means maintaining interruption of right-of-way to any intervening lane during such transfer, in absence 15 of actuation on said intervening lane.

13. A traffic control system for more than two interfering traffic lanes including signalling means to accord right-of-way to one lane while interrupting right-of-way to the other lanes, traffic actuable means in each lane, control means including timing means to operate said signalling means to accord right-of-way successively for predetermined periods to each of the said lanes in a predetermined order in response to actuation of all of the traffic actuable means, and said control means also including means responsive to non-actuation of any one of said traffic actuable means to operate said signalling means to maintain interruption of 30 right of way in and to omit accord of right of way to the lane of the non-actuated traffic actuable means.

14. A traffic control system for more than two interfering traffic lanes, including "go" and "stop" signals for each lane, traffic actuable means for each lane, and a controller comprising groups of switching means for each lane, selector means for sequentially operating said groups of switching means in predetermined order when activated, means activating said selector means in response to actuation of said traffic actuable means on a lane having a "stop" signal displayed, means causing said selector means to stop when operating the group of switching means corresponding to the said lane in which actuation occurred, to cause the "go" signal to be displayed and the "stop" signal to be extinguished on the latter lane, while "stop" signals are displayed on the other lanes, and timing means to maintain said selector means in said stopped condition for a predetermined minimum period.

15. A traffic control system for more than two interfering traffic lanes, including "go" and "stop" signals for each lane, traffic actuable means for each lane, and a controller comprising groups of switching means for each lane, selector means for sequentially operating said groups of switching means in predetermined order when activated, means maintaining "stop" signals on all lanes on which actuation has not occurred, while the selector means is sequentially operating said groups of switching means, means activating said selector means in response to actuation of a traffic actuable device on a lane having a "stop" signal, means causing said selector means to stop when operating the group of switching means corresponding to the said lane in which actuation occurred, to cause the 60 65 70 75

- "go" signal to be displayed and the "stop" signal to be extinguished on the latter lane, while "stop" signals are displayed on the other lanes, and timing means to maintain said selector means in said stopped condition for a predetermined minimum period.
16. A traffic control system including, in combination, a signalling means to be disposed at the intersection of more than two mutually interfering traffic lanes, and to accord right of way to traffic moving over one of said lanes while interrupting right of way to traffic moving over the other lanes, a timer connected to said signalling means to operate the same, a traffic actuated control for one of said lanes and connected to said timer, and means forming a part of said timer and acting in response to actuation of said traffic actuated control to cause said signalling means to transfer right of way in favor of the lane of said traffic actuated control.
17. A traffic control system for more than two mutually interfering traffic lanes including signalling means to accord right of way to one lane while interrupting right of way to the other lanes, a control means including timing means and connected to said signalling means to cause said signalling means to normally, cyclically accord right of way successively for predetermined periods to each of a plurality of said lanes, traffic actuable means associated with one of said lanes to which the right of way is not normally cyclically accorded, and means cooperating with said control means when the said traffic actuable means is operated to cause the transfer of right of way to the lane of said traffic actuable means for a predetermined minimum period followed by resumption of normal cyclic operation.
18. A traffic control system for more than two mutually interfering traffic lanes including signalling means to accord right of way to one lane while interrupting right of way to the other lanes, a control means including timing means and connected to said signalling means to cause said signalling means to normally, cyclically accord right of way successively for predetermined periods to each of a plurality of said lanes, traffic actuable means associated with one of said lanes to which the right of way is not normally cyclically accorded, and means cooperating with said control means when the said traffic actuable means is operated to cause the transfer of right of way to the lane of said traffic actuable means for a predetermined minimum period followed by resumption of normal cyclic operation.
19. A traffic control system for more than two mutually interfering traffic lanes including signalling means to accord right of way to one lane while interrupting right of way to the other lanes, a control means including timing means and connected to said signalling means to cause said signalling means to normally, cyclically accord right of way successively for predetermined periods to each of a plurality of said lanes, traffic actuable means associated with one of said lanes to which the right of way is not normally cyclically accorded, and means cooperating with said control means when the said traffic actuable means is operated to cause the transfer of right of way to the lane of said traffic actuable means for a predetermined minimum period followed by resumption of normal cyclic operation.
20. A traffic control system for more than two mutually interfering traffic lanes including signalling means comprising means to accord and means to interrupt right of way for each of the lanes, traffic actuable means in one lane, control means including timing means functioning when the said traffic actuable means is actuated while the right of way is interrupted in the said one lane, to cause the transfer of right of way to the said one lane, and means to retain the right of way in the said one lane for a predetermined minimum period before transfer to another lane can be effected.
21. A traffic control system for more than two mutually interfering traffic lanes including signalling means comprising means to accord and means to interrupt right of way for each of the lanes, traffic actuable means in one lane, control means including timing means functioning when the said traffic actuable means is actuated while the right of way is interrupted in the said one lane, to cause the transfer of right of way to the said one lane, and means to retain the right of way in the said one lane for a predetermined minimum period before transfer to another lane can be effected, and further means functioning upon actuation of said traffic actuable means during said predetermined minimum period to cause the extension of right of way beyond said minimum, and further means to limit to a predetermined maximum the extension of right of way by continued or successive actuations.
22. A traffic control system for a street intersection including a pair of signal circuits, one circuit including a "stop" signal and the other circuit including a "go" signal, a source of power therefor, a switch means movable through a cycle for alternately connecting said circuits to said source of power, means for moving said switch means at a selected speed, means operable by a unit of traffic for initiating the operation of said moving means, and means actuated by said last-named means for regulating said moving means to vary the speed of movement of said switch means, said last named means being responsive to successive actuations of said traffic-actuated means by successive units of traffic.
23. A traffic control system for the intersection of a highway and at least one street, and having the usual stop and go lights for the intersection, comprising switch mechanism for energizing said lights, and means in the highway operable by a vehicle seeking to make a left turn therefrom for controlling said switch mechanism to energize the lights both to permit the vehicle to negotiate the turn and stop traffic approaching from all other directions.
24. A traffic control system for two substantially parallel and opposite traffic lanes, comprising "stop" and "go" signals for each lane, and means responsive to a unit of traffic in one lane taking a position to execute a turn across the other lane for actuating the "go" signal for said one lane and the "stop" signal for said other lane.

25. A traffic control system for an intersection of a plurality of interfering lanes including stop and go signal circuits for the lanes, a source of power therefor, a switch mechanism movable through a cycle for alternately connecting said circuits to said source of power to successively accord right of way to the lanes, means operable by a unit of traffic for initiating the operation of said mechanism, and means operable upon actuation by another traffic unit to stop movement of said switch mechanism whereby the time length of said cycle is increased.
26. A traffic control system for more than two mutually interfering traffic lanes including signalling means to accord right of way to any one lane while interrupting right of way to the other lanes, a control means including timing means and a cyclic switching mechanism having a plurality of switching positions in its cycle and normally having operative connection with said signalling means to cause the signalling means to accord right of way cyclically and successively for time periods determined by said timing means to each of a plurality of said lanes and to maintain interruption of right of way continuously in another of said lanes, traffic actuatable means associated with said another lane, an electromagnetic device connected with said cyclic mechanism and adapted when operated to change the operative connection between said mechanism and said signalling means to accord right of way to said another lane and interrupt right of way in the remaining said lanes for a predetermined minimum time period only in a certain position in said cycle and said electromagnetic device having a connection with said traffic actuatable means to be initially so operated by actuation of the latter means, and means including a holding circuit for said electromagnetic device connected with said cyclic mechanism to maintain said device so operated through said certain position of said cycle after such initial operation and then to release said device to restore said normal operative connection.
- 45 27. A traffic control system for more than two interfering traffic lanes including signalling means for the several lanes to accord right of way over any one of said lanes while interrupting right of way over the other lanes, traffic actuated means for the several lanes, cyclic switching mechanism having more than two switching positions through which it is adapted to be operated cyclically to provide potential periods of operation of the signalling means for right of way to the several lanes in sequence, electromagnetic devices individual to the several lanes and connected respectively to the respective traffic actuated means for such lanes and to the cyclic mechanism to be operated individually from an unoperated condition to an operated condition by actuation of the respective traffic actuated means to operate in such operated condition of the respective devices the respective right of way signalling means at the respective switching positions in cooperation with said mechanism to convert the potential operating period for any of said lanes to an actual right of way operating period responsive to such actuation and to operate in such unoperated condition of the respective devices the right of way interrupting signalling means for the respective lanes, and a time controlled driving mechanism connected with the several said devices to operate said switching mechanism from one of its switching positions to another switching position responsive to the operation to operated condition of the electromagnetic device associated with said another switching position and to maintain said switching mechanism in the latter switching position for a minimum time for such actual right of way period, and holding circuit means for the respective electromagnetic devices connected with said switching mechanism to hold any such device in operated condition after operation by the traffic actuated means and into the switching position with which such device is associated to provide such actual right of way period and then to release such device.

HENRY A. HAUGH, JR. 45
